METHOD OF REMODELING SHOE LASTS

Harry Walter Lucas, Brockton, Mass., assignor to
Vulcan Corporation, Portsmouth, Ohio

Application September 19, 1936, Serial No. 101,581

3 Claims. (Cl. 144—309)

The present invention relates to a method of remodeling or rebuilding shoe lasts, and particularly to such a method wherein the contour and dimensions of the last may be altered throughout the entire fore part of the last.

In manufacturing certain types of shoes, style changes take place rapidly and, in many instances, such changes require replacement of lasts which are otherwise serviceable. Breakage and damage are also responsible for additional premature replacement of many lasts. Any factor which reduces the expense occasioned by such replacements is welcomed by the shoe manufacturer.

It is one object of this invention to provide a method of remodeling lasts which will make available to the manufacturer a satisfactory substitute for a new last, but at a low cost.

Another object of the invention is to provide a remodeled last which will have the strength of an entirely new last and will resist the stresses and strains imposed thereon during the various operations employed in the manufacture of shoes.

A further object of the invention is to provide a method of remodeling lasts, in which any desired style contour change may be made in the fore part of the remodeled last. In accordance with the method herein disclosed, such change may extend from the tip of the toe to a plane situated in the heel part of the last back of the hinge joint.

A still further object of the invention is to provide a remodeled last, which may be economically produced on a quantity production basis.

Another object of the invention is to provide a method of remodeling a last, wherein the portion of the original last to be retained may be accurately centered or aligned with the new part, thus insuring that the contour of the new part and that of the original part at the junction of the two parts will coincide.

It will be understood that the term "fore part" as it is used herein, refers to the whole portion of the last forward of the hinge, while the "back part" refers to the remaining portion of the last. In a block last, the line of demarkation between the fore and heel part will be understood to be a plane situated at the position occupied by the hinge in a two part last.

A preferred embodiment of the invention is illustrated in the drawing wherein Fig. 1 is the side elevation of a last constructed in accordance with the invention; Fig. 2 is a perspective view of a rough fore part block, processed in accordance with the invention; Fig. 3 is a perspective view

of the heel part which is to be retained in the remodeled last; Fig. 4 is a side elevation of a composite last, composed of the original heel part and the rough fore block as it appears in the last lathe before the turning operation; Fig. 5 is a detail view showing a modification of the invention.

While a hinge-last will be described herein, it will be understood that the method of the present invention is also adaptable to other types of lasts. The present invention is particularly adapted to fulfill the demands of the shoe manufacturer who wishes to change the form of his last not only in the toe and ball sections but also in the portion to the rear of the ball, including the hinge portion and a portion to the rear beyond the hinge portion.

The plane 1, at which the discarded fore part of the last is to be severed from the heel part, is situated upon the axis of the hinge or a short distance to the rear of this axis, depending upon the construction of the last which is being remodeled. In the last illustrated in the drawing, the plane 1 is situated substantially upon the axis of the hinge. It is desirable in lasts having anchor pins to retain as much wood between the rear anchor pin 2 and the plane 1 as possible, to insure that the strength of the remodeled last will be sufficient to resist the stresses imposed thereon by the shoe making operations.

The first step to carry out the invention is to remove the entire old fore part from the heel part and disconnect all of the hinge elements from the heel part, the elements in the present instance being the links and the spring which connect the two last parts. A flat face 3 is then formed on the heel part 4. Desirably, this face 3 is formed upon the heel part by sawing or otherwise shaping the heel part in the plane 1. It is desirable, but not essential, that the position of the plane 1 be selected to coincide with the plane occupied by the original hinge abutting surface 5 on the heel part, provided the structure of the original last will permit such a procedure.

The next step in the process is the formation of one member of a dove-tail joint, indicated at 6. As indicated in the drawing, this member 6 is the groove member of the joint, although it is within the scope of the invention to construct the joint with the tenon member thereof upon the heel part. The groove 6 may be formed in any suitable manner, such as by a rotary cutter having the desired dimensions of the groove.

A rough block 7 is next prepared to be united with the heel part 4. This block must be of the

proper length and width to permit the turning of the new fore part therefrom. The rear face 8 of the block 7 is given a shape complementary to that of the face 3 on the heel part which has formed thereon a tenon 9 which snugly fits within the groove 6. The face 8 may be formed in any desired manner, such as by a pair of properly shaped rotary cutters spaced correctly to produce a tenon of the proper dimensions to be received in the groove 6. The heel part 4 and the rough fore block 7 are then assembled one upon the other and cemented together.

The composite last thus produced is then placed in a suitable centering fixture wherein a center 10 is spotted in the front face of the rough fore block and in accurate alignment with the original turning axis of the heel part 4. The alignment of the composite last is obtained by placing the heel part in contact with gauging elements 15 previously adjusted to the heel part of a last which is to be used as the model in turning the remodeled lasts. This centering procedure is well known to those skilled in the art.

The composite last is then ready to be placed 20 in the turning lathe. Its heel end may be held by means of the ordinary heel dog or it may be held by means of an adjustable remodeling dog, such as that shown at 11, in Fig. 4 of the drawing. In the latter case, the dog 11 is adjusted to place the turning axis of the heel part in alignment with the lathe axis. The toe dog 12, which is, or may be, of standard construction is forced 25 into engagement with the center 10 upon the block 7.

30 A model having the desired new contour is then placed in the lathe in the usual manner and the composite last which occupies the position normally occupied by the last block is then turned in accordance with the model.

35 The last thus produced and having the desired contour, may now be converted into a two-part hinge-last and desirably before cutting the last into two parts, a pair of anchor pin holes 14 and 15 are drilled in the last. These holes are located in the usual way by means of a special drilling fixture. To divide the last, the same procedure may be followed as that employed in dividing a simple one-piece last which has been turned from a standard last block. It is within 40 the scope of the invention to produce a flexible two-part last from the block last thus far produced by the process, in any suitable manner.

45 As shown in the drawing, a saw cut is made upon the line 16 and another cut is made along the line 17, each cut extending only as far as the cylindrical portion 18 of the hinge. The material between the two cuts is then removed in the usual manner and a band saw cut is then employed to form the cylindrical portion 18 of the 50 hinge in a manner well known in the art.

To sever the two sections, a saw cut is then made, preferably upon the plane 1 and extending from the sole surface of the last to the lower extremity of the cylindrical portion 18. By thus 55 making this last saw cut upon the plane 1, the plane of the cut coincides with the plane of the original abutting face 5 of the heel part. It will be understood, however, that it is within the scope of the invention to sever the last at a 60 point to the rear of that illustrated in the drawing.

The two last parts thus produced are held to-

gether by assembling the hinge elements in proper position. A recess 19 must be formed in the finished fore part face 8 in proper position to receive the forward ends of the links 21 and the spring 22. The rear end of the links and spring are received in the recess 23 already formed in the heel part 4. The pins 24 and 2 are driven into the holes 14 and 15, and also through the holes provided therefor at the ends of the links 21 and in the eyes of the spring 22 in a manner well known to those skilled in the art. The last is then completed by removing the surplus material at the tip of the toe, smoothing by sanding, and finishing in the usual manner.

5 It will be noted that the dove-tail joint above described, extends vertically of the last. It is within the scope of the invention to construct the last with the dove-tail joint extending horizontally from side to side of the last, as shown at 25 10 in Fig. 5 of the drawing. It will also be understood that other forms of interlocking joints than that form illustrated in the drawing may be employed in practicing the invention.

I claim:

1. A method of remodeling hinge-lasts comprising severing the original last in a plane transverse to its length at or to the rear of the hinge joint, forming one member of a dove tail joint in the material of the heel part of the original last, forming the other member of the 30 said dove tail joint in the material of and at the rear face of a rough fore block, assembling and cementing the dove tail joint, turning the composite last thus formed in accordance with a selected model, separating the fore part and heel 35 part of the composite last along a path circumventing the dove tail joint to leave the joint intact but including a portion of the abutting ends of the original heel part and remodeled fore part, and inserting a flexible joint between the separated fore and heel parts of the remodeled last.

2. A method of remodeling a hinge shoe last comprising severing the original last transversely behind the hinge thereof, forming an interlocking joint upon the abutting faces of the original last 45 heel part and a new rough fore part, aligning the heel part of the composite last thus formed in a turning lathe with a model, the fore part of which is to be reproduced in the remodeled last, turning the last, and constructing a new hinge joint 50 having flat abutting faces adjacent the bottom face of the last and situated at the plane of the abutting faces of the original heel part and the new fore part.

3. The method of remodeling hinge-lasts comprising severing the last transversely near the hinge joint, forming one member of a dove tail joint on the severed end of the heel part of the original last, forming the other member of the dove tail joint on the rear end of a rough fore 60 part, connecting the new fore part and original heel part by the dove tail joint, turning the composite last thus formed in accordance with a selected model, separating the fore part and heel part of the new composite last along a path circumventing the dove tail joint to leave the joint intact but including the lower portion of the abutting ends of the original heel part and remodeled fore part, and inserting a flexible joint 65 between the separated fore and heel parts.

HARRY WALTER LUCAS.
